DOCUMENT DUPLICATING AND SORTING MACHINE

Daniel N. Yanofsky, Jericho, N.Y., assignor to
Pitney-Bowes, Inc., Stamford, Conn.

Filed Dec. 3, 1973, Ser. No. 421,150

Term of patent 14 years

Int. Cl. D16—03

U.S. Cl. D61—1 Q

FIG. 1

FIG. 2

FIG. 3

FIG. 5

FIG. 4

FIG. 1 is a perspective view of a document duplicating and sorting machine showing my new design;

FIG. 2 is a front elevational view thereof, the rear elevational view of the panel members being substantially identical and the rear elevational view of the sorting member being plain and unornamented;

FIG. 3 is a top plan view thereof;

FIG. 4 is a left side elevational view thereof; and

FIG. 5 is a right side elevational view thereof.

I claim:

The ornamental design for a document duplicating and sorting machine, as shown and described.
